DESIGN FOR A DRAWER KNOB

William A. Anderson, Los Angeles, Calif.

Application September 8, 1936, Serial No. 64,764

Term of patent 3½ years

To all whom it may concern:

Be it known that I, William A. Anderson, a citizen of the United States, residing at Los Angeles, in the county of Los Angeles and State of California, have invented a new, original, and ornamental Design for a Drawer Knob, of which the following is a specification, reference being had to the accompanying drawing, forming part thereof.

Fig. 1 is a top plan view of a drawer knob showing my new design.

Fig. 2 is a front elevation of the drawer knob shown in Fig. 1.

Fig. 3 is a rear elevation of the drawer knob shown in Fig. 1.

Fig. 4 is a perspective view of the drawer knob.

I claim:

The ornamental design for a drawer knob, as shown.

WILLIAM A. ANDERSON.
